UNITED STATES PATENT OFFICE.

CLARENCE ERNEST RUPPELT, OF CANONSBURG, PENNSYLVANIA.

LOCK SEAM FOR PIPE SECTIONS.

Application filed January 30, 1928. Serial No. 250,689.

The present invention relates to lock seams, and as here disclosed is shown as applied to stove pipes, for which it is well adapted and more particularly intended, although it is to be understood that it is not limited to that specific use.

Its adaptability to stove pipe sections lies in the fact that by its use a series of pipe sections may be nested together for packing and transportation in unlocked condition, and when installed the sections may be readily interlocked so as to give a secure fastening, and one which cannot be accidentally unlocked either by straight pull or longitudinal shifting of the interlocked edges relative to each other.

Lock seams of the same general character as that herein disclosed are broadly old, but the lock seam which I have invented has certain advantages over the generally similar type now known to me, and my invention is directed to those improvements which are set forth and claimed in the description which follows and are illustrated in the drawings herewith which form a part of this disclosure.

In the drawings:

Figure 1 is a view of a stove pipe section showing the seam, and in dotted lines the location of the interlocking elements of the seam.

Figure 2 is an enlarged view of the overlapping edges of a stove pipe section showing the lock, this view being on the interior of the pipe.

Figure 3 is a sectional view substantially on the line 3-3 of Figure 2.

Figure 4 is a sectional view substantially on the line 4-4 of Figure 2.

Figure 5 is a view substantially on the line 5-5 of Figure 2.

Figure 6 is a view of a key for disassembling the section.

Referring to the drawings by numerals, like numbers indicating like parts in the several views, 10 indicates a stove pipe section having interlocking edges 11 and 12.

The edge 11 of the stove pipe section will be given a triple fold, as shown in Figures 3 and 4 at its extreme edge, two of the plies at the point 13 being closely in contact to furnish a rigid and finished outer seam section, while the third or free ply 14 will be folded so as to give a groove or recess extending longitudinally of the seam and designed to receive the opposite edge of the pipe section to lock the parts together. The ply 14 will be provided at intervals with openings 15, preferably of rectangular shape as shown, and designed to receive and interlock with a complementary locking member formed on the opposite edge 12 of the pipe section.

The opposite edge 12 of the stove pipe section is provided at intervals corresponding with the intervals between the opening 15 in the edge 11 with interlocking projections 16 preferably, and as here shown, formed on the undersurface of the material, so that, when the seam is interlocked and the section is ready for use, the projections and interlocking elements will be on the inside of the pipe and the exterior will present a smooth, finished, seam. The projection 16 is formed by dieing or stamping up a rectangular protuberance of such dimensions as to fit snugly the opening 15, the parts being proportioned so that while the locking projection 16 will readily enter the opening 15 when the parts are brought to interlocking position, it will, nevertheless, be of such proportions as that it will prevent any shifting longitudinally of the two interlocked edges. The projection 16 is of sufficient height so as to give the abrupt ends 17 which, engaging the ends of the openings 15, will eliminate any relative endwise movement after engagement of the parts.

The projection 16 will preferably be of the form shown, that is, generally rounded throughout the greater portion of its area, but at its inner edge it will be provided with a struck up locking member 18, this member 18 being died out from the edge of the rounded projection 16, and preferably, as shown, to a point slightly beyond the plane of the top of the projection 16 so as to insure a locking member of sufficient height to securely engage the edge of the opening 15 and hold the parts against disengagement by lateral movement. The projection 16 will be slightly inset from the edge 12 of the material, and the opening 15 will be set away from the bend 19 between the ply 14 and the plies 13 so that the extreme edge 12 of the interlocking pipe section will engage

the bottom of the recess when the locking projection 16 is brought to interlocking position relative to the opening 15 in the ply 14. This gives a securely nested, thoroughly rigid, construction, and eliminates any danger of buckling under strains imposed transversely of the seam.

The construction is one which not only gives a very secure interlocking of the edges 10 of the material, and one which cannot be dislodged either by lateral pull or by longitudinal shifting, since the parts are firmly interlocked against movement in either direction, but it also lends itself, by reason of 15 its peculiar construction, to the ready assembling of the edges. The extreme flat edge 12 of the pipe may be very readily entered in the recess between the ply 14 and the plies 13 with the projection 16 and the 20 openings 15 registering, and then by applying pressure to the pipe the rounded projection 16 will readily slide into place, the relatively thin flexible section 20 of the ply 14 will snap over the locking member 18, and the parts securely interlocked and in 25 rigidly nested condition, as shown best in Figures 3 and 4.

Furthermore, the construction is one which involves only simple manufacturing 30 problems. A sheet of stock of proper dimensions may be taken in flat condition, one edge subjected to the action of dies to stamp up the interlocking projections, and this may be readily done by one dieing operation, 35 while the opposite edge may be punched to form the lock receiving openings and then folded to give the double stiffening plies and the receiving recess for the opposite edge. I regard it as of considerable 40 importance that the locking projection is inset from the edge of the material so as to leave a flat groove engaging portion, and that the receiving recess between plies 13 and the ply 14 extends some distance beyond 45 the opening 15 to receive this extended edge, for this gives a very complete and rigid seam and eliminates any possibility of the inserted edge 12 from rocking or shifting in the opening and gives a rigidity to the seam, which, without this nesting of the extreme 50 edge of the section 12 in the bottom of the recess, would not be secured.

In Figure 6, the key is shown for unlocking the joint. It comprises a rounded shank portion 22 and a flattened head portion 23. The length of the head portion is the same as the width of the thin flexible section 20. This insures against any possibility of the 55 key head extending into and catching in the locking member 18.

By placing the flat key head beneath the section 20 with the shank portion 22 at right angles thereto, a forcing of the shank portion to a parallel position with and against 60 the stove pipe will lift the section 20 suffi-

ciently to allow the locked member 18 to be easily withdrawn from the opening 15.

In Figure 4, the dotted lines show the section 20 lifted in order that the locking member may be withdrawn. The key is also 70 shown in dotted lines in Figure 2.

This unlocking feature facilitates disassembling the sectional stove pipes, and eliminates the prevailing danger of injury to the locking members, as is the case when 75 any sharp pointed tool is used to pry them open.

Obviously, changes in the make-up of the seam may be made without departing from the range of my invention or from the scope 80 of the claims in which I have specified that which is new.

I claim:

1. A lock seam of the character described, comprising a recessed member a wall of 85 which is provided with an interlocking opening, a recess engaging member, and an interlocking projection on said last-named member the ends of which engage the ends of the interlocking opening to prevent relative longitudinal movement of said members, and interlocking means on said projection to prevent relative lateral movement of said members.

2. A lock seam of the character described, 95 comprising a recessed member a wall of which is provided with an interlocking opening, a recess engaging member, an interlocking projection having a curved upper surface and substantially vertical ends to 100 engage the end walls of the opening and lock said members against relative longitudinal movement, and a projection extending laterally from said first-named projection between its ends to engage a side wall of 105 said opening and prevent relative lateral movements of said members.

3. A lock seam of the character described, comprising a recessed member a wall of 110 which is provided with an interlocking opening, a recess engaging member, a substantially half-round interlocking projection having substantially vertical ends on said last-named member to engage the opening and lock said members against relative 115 longitudinal movement, and a second projection extending laterally from said first-named projection between its ends and having a substantially vertical face to engage said opening and lock said members against 120 relative lateral movement, said last-named projection extending above the plane of the top of said first-named projection.

4. In a lock seam construction, an interlocking member having a series of integral 125 rounded projections struck from the material thereof and provided with substantially vertical ends, and a second locking projection struck from the first-named projection between and at right angles to its ends. 130

5. In a lock seam construction, an interlocking member having a series of integral rounded projections struck from the material thereof and provided with substantially vertical ends, and a second locking projection struck from the first-named projection between and at right angles to its ends, said

second projection extending above the plane of the top of said first-named projection and having a substantially vertical end. ¹⁰

In testimony whereof I have hereunto set my hand.

CLARENCE E. RUPPELT.
